UNITED STATES PATENT OFFICE.

ANDREW W. REDIN AND ROY W. REDIN, OF ROCKFORD, ILLINOIS.

MECHANICAL MOVEMENT.

Application filed November 15, 1923. Serial No. 674,797.

To all whom it may concern:

Be it known that we, ANDREW W. REDIN and ROY W. REDIN, citizens of the United States, residing at Rockford, in the county 5 of Winnebago and State of Illinois, have invented certain new and useful Improvements in Mechanical Movements, of which the following is a specification.

This invention relates to a mechanical 10 movement of the character disclosed in Patent No. 613,199, dated Oct. 25, 1898, for mechanical movement, which provides mechanism for producing an intermittently rotary and oscillatory movement from continuous rotary movement; and the primary 15 object of the present invention is to provide a generally improved and simplified mechanical movement of this character.

More particularly, our invention contemplates 20 the provision of novel mechanism so operable between a pair of rotary members as to transmit either rotary or oscillatory movement to one from continuous rotary movement of the other, such mechanism being improved especially in regard to the 25 means for transmitting the movement between said rotary members, and further in regard to the means for effecting the change from one movement to the other.

Our invention while generally applicable 30 as a mechanical movement is especially adapted for use in circular knitting machines for imparting either rotary or oscillatory movement to the needle cylinder or to 35 the needle cams.

Other objects will be appreciated by those 40 skilled in this art as the invention becomes better understood by reference to the following description when considered in connection with the accompanying drawings, in which—

Figure 1 is a side elevation of mechanism for transmitting a mechanical movement in accordance with our invention;

Fig. 2 is a sectional view taken substantially on the line 2—2 of Fig. 1;

Fig. 3 is an enlarged fragmentary view looking at the left hand end of Fig. 1;

Fig. 4 is a detail section taken on the 50 line 4—4 of Fig. 1;

Figs. 5 and 6 are detail sections taken on the lines 5—5 and 6—6, respectively, of Fig. 3; and

Figs. 7 to 12 inclusive, are a series of

diagrammatic views showing different 55 stages of the mechanical movement, which will be explained more fully hereinafter.

The two rotary members between which it is desired to transmit motion are in the present instance in the form of spur gears 60 13 and 14 suitably journaled in concentric relation on bearing brackets 15 and 16. Spur pinions 17 and 18 mesh with the gears 13 and 14 respectively, the pinion 17 being continuously driven as by a belt and pulley, 65 and the pinion 18 being the driven element for transmitting the intermittent rotary oscillatory movement. In the application of our mechanical movement to a circular knitting machine, the pinion 18 drives a shaft 70 19 through the agency of bevel gears 21, which shaft in turn drives the needle cylinder or the cams according to the type of knitting machine.

Our invention has to do with the means 75 operative between the rotary members 13 and 14 for transmitting intermittent rotary and oscillatory movement from one to the other. Each of said members carries a drive-transmitting part, that for the gear 80 13 being the inner end 22 of a movable wrist pin, and for the gear 14 a fixed lug 23, likewise part of a wrist pin. These parts overlap so that by moving the part 22 radially it may be brought into and out 85 of a path coinciding with the part 23. With these parts in alignment, rotary motion will be transmitted directly thereby, from the member 13 to the member 14. When said parts are out of alignment or 90 registration, motion will be transmitted therebetween by means of a connector which transforms rotary movement of the part 22 to oscillatory movement of the part 23. The means for shifting said part 22 into and 95 out of said registration or connection with the part 23 and the means for transforming movement between said parts will now be described in order.

Referring more particularly to Figs. 3 100 and 6, it will be observed that the part 22 is in the form of a wrist pin fixed in a slide designated generally by 24 mounted for movement lengthwise in a radial slot or aperture 25 in the rotary member 13. Said 105 slide has retaining or side walls 26 which overlap the sides of the member 13 and hold the slide against lateral displacement. The

slide carries on its side opposite from the projecting part 22, a cam follower in the form of a roller 27. This roller is adapted to be actuated by either of the cams 28 or 29 for moving the slide radially, and consequently moving the part 22 into and out of registration with the part 23 for the purpose above referred to.

Said cams are fixed respectively to carriers 31 and 32 mounted on suitable ways 33 on the bracket 15 for movement in a plane at right angles to the plane of rotation of the member 13. Means is provided for moving either one of said cams into the path of the follower roller 27 and the other out of said path, so that only one of the cams functions at a time. This means at present consists of a cam slide 34 movable in a plane transverse to the cam carriers 32 and having formed therein a pair of oppositely inclined slots 35 and 36 in which are respectively located pins 37 and 38 fixed to the cam carriers 31 and 32. Any suitable means may be provided for shifting the cam slide 34, such for example as an operating link 39. In the full line position shown in Figs. 3 and 5, the cam slide 34 has been moved to its uppermost position, thereby advancing the cam 29 into the path of the follower 27 and withdrawing the cam 28 from said path. Upon shifting the cam slide 34 in the opposite direction, it will be manifest that by action of the inclined slots 35 and 36 on the pins 37 and 38 respectively, the position of the cams 28 and 29 will be reversed as indicated in dotted lines on Fig. 5. When the member 13 is revolved in a counterclockwise direction viewing Fig. 3, its cam follower roller 27 will be moved across the face of either one or the other of the cams 28 and 29 according to the position thereof, and will be moved radially to an inner or an outer position, according to the circumstances. The cam 29 when in operative position, serves to move the roller 27, and consequently the slide 24 and drive-transmitting part 22, inwardly on the rotary member 13 to the full line position shown in Fig. 5. The parts will remain in this position during continued rotation until changed by the reversal of the position of the cams, in which event the cam 28 serves to move the roller 27 outwardly as will be obvious. In the inner position referred to, the drive-transmitting part 22 is out of registration with its complementary part 23, and in said outermost position said parts are in registration for transmitting the continuous rotary movement.

Means is provided for locking the slide 24 in its inner and outer positions, consisting in the present instance of a pair of locking pins 41 and 42 (Figs. 3 and 6) carried in a casing 43 inserted in the member 13 and fixed with respect thereto. Said locking

pins are respectively urged by compression springs 44 against the slide 24 for entering recesses 45 and 46 therein. Each pin has a lateral projection 47 passing through a slot in the casing 43 and adapted to be engaged by a finger 48 for withdrawing the pin from its respective recess. These fingers 48 are fixed to an oscillatory part 49 on the casing 43 which carries a cam follower roller 51 adapted to be actuated by either of the cams 28 or 29 in advance of the roller 27. The cam follower roller 51 and its fingers 48 are so relatively arranged that when the slide 24 is to be moved to its inner position by the cam 28, the roller 51 will be actuated to withdraw the locking pin 42 and leave the pin 41 free to enter its respective recess in said slide under the influence of its spring 44. Thus, as the parts are shown in Fig. 3, the part 49 has been swung in a counter-clockwise direction by the action of the cam 29 on the roller 51 so as to withdraw the pin 42 from the recess 46 and allow the pin 41 to enter the recess 45. However, the pin 41 does not enter the recess until the slide 24 has been moved inwardly by subsequent action of the cam 29 on the roller 27, which brings said recess 45 into alignment with the pin 41, allowing the latter to enter, in which position the parts are shown in full lines in Fig. 3. It will be manifest that when the cam 28 is put into action, the cam followers 51 and 27 will be actuated in succession, thereby unlocking the slide and moving it to the outer position, in which it will be locked by the pin 42.

From the foregoing, it will be apparent that by shifting the cams 28 and 29, which in practice may be done either at will or automatically, as the case may require, the drive-transmitting part 22 will be moved into and out of driving relation with the part 23 and locked in each position for the purpose described above.

Referring now to the connector means for transforming the movement between the parts 22 and 23 when they are out of alignment, it will be observed that this comprises, generally stated, an oscillatory arm 52 and a pair of links 53 and 54 connecting said arm 52 with the parts 22 and 23 respectively. In the present embodiment of our invention, the oscillatory arm 52 has a fixed fulcrum 55 and the links 53 and 54 are concentrically, pivotally connected at their ends 56 to the outer end of the arm 52. These links act as pitmen in relation to the members 13 and 14. The link or pitman 53 connects to the wrist pin portion 57 of the part 22, as shown in Fig. 6, and the link 54 has a similar connection with the wrist pin 58, which as shown on Fig. 4, is fixed to the member 14 and carries the drive-transmitting part 23.

The operation of this oscillatory connector

will be readily understood by reference to Figs. 7 to 12 inclusive, which show diagrammatically the different positions of the connector. The driving member 13 and consequently the drive-transmitting part 22, revolves in a counterclockwise direction, viewing said figures. In Fig. 7, the parts 22 and 23 are in driving alignment, thereby establishing direct connection between the members 13 and 14 so that the latter will be continuously rotated, it being noted that this relation of the parts 22 and 23 is maintained during such rotation by reason of the part 23 being fixed to the driven member 14. During such rotation the connector parts 52, 53 and 54 simply oscillate idly in the manner of an articulated pitman. In said position, the wrist pin centers of the parts 22 and 23 are concentric, and in order to change the drive to the member 14 from continuous rotary to oscillatory movement, one of said centers will be moved to eccentric relation, as for example by movement of the member 22 inwardly, by action of the cam 29 to the position shown in Fig. 8 in which said part 22 is out of driving alignment with the part 23. As the part 22 continues in its circular travel in a counterclockwise direction, the center 59 will be swung downwardly until the center of the part 22 passes the point shown in Fig. 9, at which the arc 61 of the link 53 is tangential to the arc 62. During this portion of the cycle, that is, from the time the parts 22 and 23 have been disconnected until the part 22 reaches the position shown in Fig. 9, the member 14 will be moved in a counterclockwise direction by reason of the downward travel of the link 54. As the part 22 continues in its circular path in a counterclockwise direction, as shown in Fig. 10, the point 59 will be drawn upwardly, thereby imparting a thrust through the link 54, causing the member 14 to be oscillated in a clockwise direction, as indicated by the arrows in said figure. The limit of this reverse movement of the member 14 is reached when the part 22 has traveled approximately 180 degrees, that is, to the point shown in Fig. 10, diametrically opposite from the tangential position referred to and at which the point 59 reaches its highest elevation. In the present instance, the member 14 will be reversed through about 90 degrees. As the part 22 continues in its travel, the motion of the part 14 will be reversed as shown in Fig. 11, and will continue to the limit of such movement as shown in Fig. 9. It will be manifest that while the parts 22 and 23 are out of driving alignment, the driven member 14 will be oscillated approximately 90 degrees in each direction for each revolution of the driving member 13. In Fig. 12, we have shown the approximate point at which the member

22 will be moved back into driving alignment with the part 23 by the action of the cam 28, thus establishing direct driving connection between the members 13 and 14.

From the foregoing it will be manifest that by shifting the control member 39 either of the cams 28 or 29 may be brought into action for shifting the drive-transmitting part 22 into and out of driving alignment with the part 23 for the purpose of transmitting from the driving member 13 to the driven member 14 either rotary or oscillatory movement. The means for accomplishing this transmission of motion comprises but comparatively few parts, arranged in compact relation, is positive in its action, and does not impose undue or excessive frictional resistance between cooperating parts. The mechanism is therefore, well suited for use in different automatic machines, where continuous operation for long periods is desired and is as mentioned above, particularly desirable in connection with knitting machines.

It is believed that the foregoing conveys a clear understanding of the objects prefaced above, and while we have illustrated but a single working embodiment, it should be understood that changes might be made in the construction and arrangement of parts without departing from the spirit and scope of the invention as expressed in the appended claims.

We claim:

1. In a mechanical movement, in combination, a pair of concentric rotary members, a slide shiftable radially on one of said members and equipped on the inner side thereof with a drive-transmitting part and on its outer side with a cam follower, a drive-transmitting part on the inner side of the other rotary member and adapted to be intermittently driven by the first mentioned drive-transmitting part, cams adapted to be moved into and out of the path of said follower for moving its drive-transmitting part into and out of said driving connection, and means operative between said drive-transmitting parts for transmitting oscillatory movement to the driven part when they are disconnected.

2. In a mechanical movement, in combination, a pair of concentric rotary members, a slide shiftable radially on one of said members and equipped on the inner side thereof with a drive-transmitting part and on its outer side with a cam follower, a drive-transmitting part on the inner side of the other rotary member and adapted to be intermittently driven by the first mentioned drive-transmitting part, cams adapted to be moved into and out of the path of said follower for moving its drive-transmitting part into and out of said driving connection, and means operative between said drive-

transmitting parts for transmitting oscillatory movement to the driven part when they are disconnected, said means comprising an oscillatory arm and a pair of links, each link being connected to a drive-transmitting part and pivotally connected to the oscillatory arm.

3. In a mechanical movement, in combination, a pair of rotary members concentrically mounted and each provided with a wrist pin having a part adapted to be brought into and out of driving connection, one of said wrist pins being radially adjustable to become axially concentric or eccentric with respect to the other, whereby to establish direct driving connection between said members when in said concentric position, means operative between said wrist pins for transmitting oscillatory movement to one member from rotary movement of the other when said wrist pins are in said eccentric relation, a cam follower roller connected with said adjustable wrist pin, and cam faces for operating said roller to move its wrist pin into and out of said concentric and eccentric positions.

4. In a mechanical movement, in combination, a pair of rotary members concentrically mounted and each provided with a wrist pin having a part adapted to be brought into and out of driving connection, one of said wrist pins being radially adjustable to become axially concentric or eccentric with respect to the other, whereby to establish direct driving connection between said members when in said concentric position, means operative between said wrist pins for transmitting oscillatory movement to one member from rotary movement of the other when said wrist pins are in said eccentric relation, a cam follower roller connected with said adjustable wrist pin, cam faces for operating said roller to move its wrist pin into and out of said concentric and eccentric positions, and means on one of said members for locking

said adjustable wrist pin in its several operative positions.

5. In a mechanical movement, in combination, a pair of rotary members, a drive-transmitting part on each member, one being fixed and the other radially movable into and out of driving alignment with the fixed part, a slide carrying said movable drive-transmitting part and equipped with a cam follower roller, means for locking said slide in its several operative positions, a cam follower roller for actuating said locking means, cams operable on said rollers for releasing said locking means and moving the slide to said operative positions, and means operative between said drive-transmitting parts for transmitting oscillatory movement to one of said members from rotary movement of the other when said parts are out of driving alignment.

6. In a mechanical movement, in combination, a pair of rotary members, a drive-transmitting part on each member, one being fixed and the other radially movable into and out of driving alignment with the fixed part, a slide carrying said movable drive-transmitting part and equipped with a cam follower roller, means for locking said slide in its several operative positions, a cam follower roller for actuating said locking means, cams operable on said rollers for releasing said locking means and moving the slide to said operative positions, and means operative between said drive-transmitting parts for transmitting oscillatory movement to one of said members from rotary movement of the other when said parts are out of driving alignment, comprising an oscillatory arm and a pair of links pivotally connected at one end to said arm and each connected at its opposite end to one of said drive-transmitting parts.

ANDREW W. REDIN.
ROY W. REDIN.
